FLOOR SWEEPING MAGNET DEVICE

Roswell H. Stearns, Wauwatosa, Wis., assignor
to Stearns Magnetic Mfg. Co., Milwaukee, Wis.,
a corporation of Wisconsin

Application June 22, 1944, Serial No. 541,601

6 Claims. (Cl. 209—215)

1

This invention relates to a floor sweeping magnet device.

Objects of this invention are to provide a floor sweeping magnet device which is so constructed that it may be pushed across a floor, parking lot, or other surface and will clean such surface of magnetic particles, such as nails, screws and chips, and will recover small lost tools provided they are of magnetic material.

Further objects are to provide a floor sweeping magnet device which is very similar in appearance to an ordinary type of floor sweeper and which may be handled with the same facility as an ordinary floor sweeper, but which instead of the customary construction of a floor sweeper is so made that a revolving drum is provided and is associated with magnets located interiorly of the drum and arranged to cause material to be held to the lower and forward side of the drum, the drum being revolved so as to bring the material over the top of the drum and the magnets being so arranged as to cause release of the material on the rear side of the drum, a suitable removable catch pan being provided for the discharged magnetic material.

In greater detail further objects are to provide a floor sweeping magnet device in which a non-magnetic revolving drum surrounds a series of permanent magnets provided with contoured poles whose lower and forward portions are in close proximity to the inner periphery of the drum and whose rear portions are spaced from the inner periphery of the drum, the magnet body itself between the poles being composed of a high grade permanent magnetic material which is readily obtainable on the open market.

Further objects are to provide a floor sweeping magnet device which is so made that the drum surrounding the permanent magnets is driven from one or more wheels on which the chassis is carried and is rotated only when the device is pushed in a forward direction, an overrunning clutch being provided to interrupt the operative connection between the drum and the wheels when the device is drawn rearwardly, the construction thus enabling the operator to freely push the device under machines and tables and withdraw it without any danger of the reverse rotation of the drum.

Further objects are to provide a floor sweeping magnet device in which a chassis carries a revolvable drum, the device having a series of permanent magnets located within the drum and adjustably carried so that they may be rocked about the axis of the drum and locked in their adjusted position, means also being provided for raising or lowering the drum with reference to the floor or surface over which the device is adapted to be passed.

2

An embodiment of the invention is shown in the accompanying drawings, in which:

Figure 1 is a vertical sectional view through the device, such view corresponding to a section on the line 1—1 of Figure 2.

Figure 2 is a plan view of the device, partly broken away and partly in section.

Figure 3 is an enlarged sectional view on the line 3—3 of Figure 2.

10 Referring to the drawings, it will be seen that the device comprises generally an open chassis or frame which is composed of side members 1 joined by a forward non-magnetic tie rod 2 and a rear tie rod 3. This chassis is carried by a pair 15 of rear rubber-tired wheels 4 and a pair of small forward casters 5 which are adapted to pivot about vertical axes in the customary manner for casters. Each caster projects downwardly from the forward bracket 6 which are joined by a non-magnetic bumper or transverse guard 7 preferably of angular construction as shown in Figure 1. A rearwardly projecting manipulating handle 8 is provided with a pair of forward arms 9 which are pivotally mounted as indicated at 10 on the inner 20 sides of the chassis.

A revolvably mounted cylindrical drum 11 is provided and is carried by non-magnetic end discs 12 which are rigid with a large gear 13. The gear 13 meshes with a smaller gear 14 carried by a 30 rearwardly located transverse shaft 15. The shaft 15 carries a pair of pinions 16 at opposite ends which are loosely mounted on the shaft and are freely revolvable thereon. Operative connection between the gears 16 and the shaft is provided by means of overrunning clutches indicated generally at 17 in Figure 2. The gears 16 mesh with internal gears 18 carried by the wheels 4. The overrunning clutches 17 are so arranged that the drum 11 is rotated only when the device is 40 pushed in a forwardly direction. The gear train is so arranged that the drum rotates in a counterclockwise direction when the device is pushed forwardly, as viewed in Figure 1.

A removable catch pan 19 is carried rearwardly 45 of the drum 11, as shown most clearly in Figure 1. The catch pan 19 rests at its forward end upon a transversely extending bar 20 which is provided with threaded end portions supported from the chassis and arranged to adjust the bar upwardly or downwardly as desired. Suitable lugs 21 project downwardly from the lower forward end of the pan 19 and are positioned on opposite sides of the bar 20. The rear portion of the pan is supported by a pair of hooks 22 which hook over the rear tie rod 3.

The revolvable drum 11 is housed within a curved casing 23 which is spaced from the drum, as shown most clearly in Figure 1. The casing 23 is

formed of stainless steel or other non-magnetic material. The casing or housing 23 is removably held to the side frames 1 of the chassis by means of screws or other suitable fastening means 24, suitable slugs 25 being provided on the side frames 1.

A plurality of permanent magnet units are positioned within the drum and are carried by a transverse fixed shaft which is adjustably supported from the side frames 1 of the chassis. The shaft, as shown most clearly in Figure 2, is composed of a hollow central portion 26 supported by shouldered end studs or stub shafts 27 which are adjustably clamped as indicated at 28 to the side frames 1 of the chassis. The portion 26 of the shaft is made of non-magnetic material, such as stainless steel for instance, and if desired the stub shafts 27 are also formed of non-magnetic material. Suitable ball bearings indicated at 29 are provided between the end disks 12 and the stub shafts 27.

This composite transverse shaft composed of the members 26 and 27 carries a plurality of permanent magnet units. Each permanent magnet unit is provided with a pair of spaced pole pieces 30 between which a permanent magnet body portion 31 is rigidly clamped by means of screws or bolts 32, suitable notches being provided in the body portion 31 for the reception of a portion of the bolts 32 to thus lock the body portion 31 against rotation with reference to the pole pieces.

It is to be noted from Figure 1 that the forward and lower part of the body portions 31 of the permanent magnets is extended radially to a greater distance than the upper and rear portions thereof. The side faces of the body portions 31 are accurately ground or machined and the corresponding contacting faces of the pole pieces 30 are also accurately finished so as to get a true face to face contact between the side faces of the body portions 31 and the corresponding pole pieces. The bolts or screws 32 are headed and pass freely through one of the pole pieces of each unit and are threaded at their other ends and screwed into the other pole piece of such unit. These bolts or screws are of non-magnetic material.

The permanent magnet units are locked to the shaft by means of set screws 33 carried by the pole pieces 30, as shown in Figure 3. The body portion 31 of the permanent magnet units is composed of a high grade permanent magnet material, such as "Alnico," and the pole pieces 30 are formed of mild steel or other suitable material. They are contoured so as to be in close proximity to the inner periphery of the drum at the lower and forward portions of the drum and at the upper portion of the drum and are cut away on their rear sides so as to be spaced away from the rear portion of the drum. For instance, the surface 34, see Figure 2, of the pole pieces 30 may be circular and the rear surface 35 is cut away. Permanent magnet units are arranged so that their pole pieces are of alternate polarity, as shown in Figure 2, and are spaced from each other. The construction is such that an intense magnetic field is produced throughout substantially the entire surface of the revolving drum 11 on its forward and lower side.

As maybe seen from Figure 1, the lower portion of the drum is arranged in proximity to the floor or other surface over which the device is adapted to be pushed. The construction is such

that the drum may be raised or lowered with reference to the floor. A convenient way of doing this is to provide the end brackets 6 with upturned portions 36 which are slotted as indicated at 37 and which are secured by means of bolts 38 to the side frames 1.

When the bolts are loosened, it is obvious that the drum may be raised or lowered as required for the particular type of material to be removed from the floor. The forward guard or bumper 7 pushes away any excessively large material and thereby prevents the picking up of excessively large material which might wedge between the housing 23 and the drum 11.

In using the device the operator merely pushes it across the floor. The gear train transmits motion to the drum 11 and causes it to rotate backwardly or in a counterclockwise direction as viewed in Figure 1. When the device passes over

magnetic material, it is attracted to the drum and held against the drum and is carried upwardly and over the drum and is released on the rear side of the drum adjacent the upper portion of said drum and falls into the catch pan 19.

The operator may clear the floor beneath machines or tables by first pushing the device under the table and then pulling the device rearwardly. The rearward motion does not cause rotation of the drum. The drum merely continues rotating from its own momentum until it is again pushed forwardly. Obviously when the catch pan 19 is filled with discharged magnetic material, it is detached and is dumped, a suitable handle being provided as shown to facilitate handling of the pan.

It will be seen that a floor sweeping magnet device has been provided by this invention which will rapidly remove magnetic material from floors, parking lots, or other surfaces.

It will be seen further that the device is very easy to operate and does not require any particular skill on the part of the operator.

It is to be understood that variations may be made in the exact design of the device without departing from the spirit of this invention. It is intended, for instance, that any suitable means may be employed for propelling the device across the floor or other surface to be cleaned of magnetic material, whether it be a pushing or a pulling handle or other suitable means.

Also it is to be understood that although a catch pan has been shown for the reception of the discharged magnetic material, whatever this expression appears it is intended to cover any suitable catch means, whether it is in a strict sense a pan or is some other construction or shape.

In using the expression "floor sweeping magnet" it is intended that this expression be interpreted in the sense that the magnetic flux is caused to sweep across the floor to thus pick up and collect magnetic material and is not used in the sense of brushing by mechanical contact of bristles or other members with the floor. In other words, the expression "sweeping" is intended in the broader sense of traversing or traveling across the floor or other surface.

The expression "floor" wherever used is intended to cover any surface on which the device

Although this invention has been described in considerable detail, it is to be understood that such description is intended as illustrative rather than limiting, as the invention may be variously embodied and is to be interpreted as claimed.

I claim:

1. A floor sweeping magnet device comprising a frame, supporting wheels revolvably carried by said frame, means for propelling said frame, a revolvable drum, means for causing rotation of said drum in a reverse direction from the direction of rotation of said wheels when said frame travels in one direction, a plurality of magnets located within said drum and having poles in proximity to the inner periphery of said drum adjacent the bottom and at one side of said drum and being spaced from the inner periphery of said drum at the other side of said drum, and a catch pan located adjacent said other side of said drum, said device being arranged to cause the under side of said drum to travel faster over the floor in said one direction than the rate of travel of said device in the said one direction to avoid wedging of magnetic material between the drum and the floor, whereby when said device is propelled across the floor in the said one direction magnetic material is picked up on said drum and delivered to said pan by said drum.

2. A floor sweeping magnet device comprising a frame, wheels supporting said frame, means for propelling said frame, a revolvable drum extending transversely of said frame, power transmitting means for driving said drum from at least one of said wheels in a reverse direction from the direction of rotation of said wheels when said frame travels in one direction, a plurality of magnets located within said drum and having poles in proximity to the inner periphery of said drum at the front and bottom portion of said drum and being spaced from the inner periphery of said drum at the rear side of said drum, and a catch pan adjacent the rear side of said drum, the under side of said drum being arranged to travel in said one direction over the floor at a faster rate than the rate of travel of said device to avoid wedging of magnetic material between the drum and the floor, whereby when said device is propelled across the floor in the said one direction magnetic material is picked up on said drum and is delivered to said pan by said drum.

3. A floor sweeping magnet device comprising a frame, wheels supporting said frame, means for propelling said frame, a revolvable drum extending transversely of said frame, power transmitting means including an overrunning clutch for driving said drum from at least one of said wheels in a reverse direction to the direction of rotation of said wheels when said frame travels forwardly, a plurality of magnets located within said drum and having poles in proximity to the periphery of said drum at the front and bottom portion of said drum and being spaced from the inner periphery of said drum at the rear side of said drum, and a catch pan adjacent the rear side of said drum for catching material discharged from the upper portion of said drum, whereby when said device is propelled forwardly across the floor magnetic material is picked up on said drum and is delivered to said pan by said drum, said overrunning clutch acting to interrupt said power transmitting means when said device is moved backwardly, the under side of said drum being arranged to travel forwardly faster over the floor than the rate of travel of said device to avoid wedging of magnetic material between the drum 70 and the floor.

4. A floor sweeping magnet device comprising a frame, wheels supporting said frame, means for propelling said frame, a revolvable drum extend-

ing transversely of said frame, power transmitting means for rotating said drum from at least one of said wheels in a reverse direction from the direction of rotation of said wheels when said frame travels in one direction, a plurality of permanent magnets located within said drum and mounted as a unitary assembly and adapted to be adjusted by rocking said unitary assembly about the axis of said drum, means carried by said frame for supporting said unitary assembly and including means for locking said unitary assembly in adjusted position, said magnets having pole pieces whose forward and lower parts are in close proximity to the inner periphery of said drum and whose rear parts are spaced from the inner periphery of said drum, and a catch pan adjacent the rear side of said drum for catching material discharged from the upper portion of said drum, whereby when said device is propelled across the floor magnetic material is picked up on said drum and deposited in said pan.

5. A floor sweeping magnet device comprising a frame, wheels supporting said frame, means for propelling said frame, a revolvably mounted drum, power transmitting means for driving said drum from at least one of said wheels, a transverse shaft carried by said frame and extending through said drum and adapted to be rocked about its axis, means for locking said shaft to said frame, a plurality of permanent magnet units mounted on said shaft and located within said drum, said magnet units producing a magnetic field from adjacent the lower portion of said drum to adjacent the top of said drum on one side thereof, a catch pan adjacent the other side of said drum, and means for adjusting the spacing of said drum from the floor.

6. A floor sweeping magnet device comprising a frame, wheels supporting said frame, a transversely positioned and revolvably mounted drum, magnetic means located within said drum for producing a magnetic field adjacent the lower and forward side of said drum to adjacent the upper part of said drum, a catch pan adjacent the rear side of said drum for catching material discharged from the upper portion of said drum, power transmitting means for driving said drum from at least one of said wheels in a reverse direction from the direction of rotation of said wheels when said frame travels in one direction, a hood spaced from and covering said drum, and a transversely extending guard member located in advance of said drum and spaced upwardly from the floor for pushing away material exceeding a predetermined size.
